(57) **CLAIM**

The ornamental design for a safe resembling studio rack gear, as shown and described.

DESCRIPTION

FIG. 1 is a front perspective view of a safe resembling studio rack gear showing my new design, shown in a used condition mounted in a rack shown in broken lines;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another front perspective view thereof with the safe in an open position.

The broken lines shown in the drawings represent portions of the safe resembling studio rack gear that form no part of the claimed design.
